to Maryland Distillery, Inc., Relay, Md., a cor-
poration of Maryland

Application December 12, 1935, Serial No. 60,033

Term of patent 14 years

To all whom it may concern:

Be it known that I, Edwin M. Fleischmann, a citizen of the United States, residing at Baltimore, county of Baltimore, Maryland, have invented a new, original, and ornamental Design for a Bottle, of which the following is a specification, reference being had to the accompanying drawing forming part thereof.

Figure 1 is a front view;

Figure 2 is a rear view; and

Figure 3 is a bottom view of a bottle showing my new design.

The characteristic features of my design reside in application of a drum motif to a bottle, the body portion of the bottle depicting a drum in elevation, said drum having a stippled surface, and the upper drum head being depicted on the shoulder of the bottle as broken whereby the bottle neck projects through the broken drum head.

I claim:

The ornamental design for a bottle, as shown and described.

EDWIN M. FLEISCHMANN.
